UNITED STATES PATENT OFFICE.

GEORGE N. SAEGMULLER, OF ROCHESTER, NEW YORK. ASSIGNOR TO BAUSCH, LOMB, SAEGMULLER COMPANY, OF ROCHESTER, NEW YORK, A CORPORATION OF NEW YORK.

VARIABLE-POWER TELESCOPE.

No. 878,661.

Specification of Letters Patent.

Patented Dec. 18, 1906.

Application filed April 16, 1906. Serial No. 312,016.

To all whom it may concern:

Be it known that I, GEORGE N. SAEGMULLER, a citizen of the United States, residing at Rochester, in the county of Monroe, State of New York, have invented certain new and useful improvements in Variable - Power Telescopes, of which the following is a specification, reference being had therein to the accompanying drawings.

10 This invention relates to a variable-power telescope, and particularly to an instrument of that character adapted for use as a transit or surveying instrument.

15 The invention has for an object to provide a novel and improved construction of means for shifting the lens-tubes carrying the erector and eyepiece systems toward and from each other and also jointly adjusting said systems while retaining the other adjusted relation,

20 whereby the instrument may be adapted for either high or lower power—that is, a wide field of extended vision or a narrow field, with a more clear definition of the object viewed.

Another and further object of the invention is to provide a novel construction of adjusting-sleeves mounted upon the lens-tubes and in the main tube of the instrument, whereby the adjusting-heads of such sleeves are directly adjacent to each other and the 30 controlling head for the eyepiece system graduated to indicate the movement thereof relative to its cooperating erector system.

Other and further objects and advantages of the invention will be hereinafter fully set forth and the novel features thereof defined by the appended claims.

In the drawings, Figure 1 is a longitudinal section through the invention applied to a transit-telescope. Fig. 2 is a similar enlarged section of the lens-tubes and through the adjusting means. Fig. 3 is a front elevation of the adjusting-head for the eyepiece-tube. Figs. 4, 5, 6, and 7 are detail perspectives separated of the erector-tube and the means for adjusting the same, and Figs. 8, 9, 10, and 11 are similar views of the eyepiece-tube and its adjusting means.

Like numerals of reference indicate like parts throughout the several views of the drawings.

The numeral 1 designates the telescope-casing, which may be of any desired character or size and which is provided at one end with

the usual objective lens 2 and intermediate of its ends with the adjusting-frame 3 of ordinary construction for supporting the cross-lines or hairs. At the opposite end of the casing from the objective lens a supporting-cap 4 is secured by means of the threaded portion 5 thereof engaging the inner wall of the 60 casing, and this cap is provided with the inwardly-extending tube 6, provided with the straight slot 7 therein. Within this cap and the tube thereof an adjusting-sleeve 8 is disposed and the cap secured thereon by means of the threaded ring 9, engaging the portion 10 of the sleeve and adapted to be locked in position thereon by a set-screw 11. The sleeve 8 is provided with an adjusting-head 12 and with a curved slot 13, extending peripherally thereof for one-half of its circumference. Within this sleeve the tube 14, carrying the system of erector-lenses or any other desired arrangement of lenses, is inserted and secured in position by means of 75 the block 15, which extends through both the curved slot 13 of the sleeve and the straight slot 7 of the cap, as shown in Fig. 2, and is removably secured in position by means of the screw 16 there shown.

80 The eyepiece end of the erector-tube is inferiorly threaded and adapted to receive the collar 17, provided with the threads 18 to engage the threaded portion. This collar is provided with a straight slot 19, and disposed within the collar is the eyepiece-adjusting sleeve 20, which is formed with the head 21, having graduations 22 upon its outer face, as indicated in Fig. 3, and adapted for movement relative to a graduation 24, 85 carried upon the eyepiece-tube 25. The sleeve 20 is provided with a curved circumferential slot 26, similar to that described in the sleeve 8. The sleeve 20 is secured within the collar 17 by means of the threaded ring 91, mounted thereon. Within the sleeve 20 the eyepiece-tube 25 extends and is secured in position by means of the block 27, extending through the slots 26 and 19 and removably secured in position by a screw 28, 95 as shown in Fig. 2. Any desired form of eyepiece, as shown at 29, may be provided and removably attached by threads 30 to the eyepiece-tube.

100 From the foregoing description it will be seen that the eyepiece-tube is carried by the

2
erector-tube and adjustable therewith, and for the purpose of varying the relation between the eyepiece lens system and that of the erector the eyepiece is adjustable relative to the erector by means of the head 21 in order to vary the magnifying power of the telescope, and both of these tubes are jointly adjustable in their adjusted relation to each other by means of the head 12, controlling the erector-tube, which is essential for securing the proper focus relative to the cross-lines and objective lens.

5 This invention is particularly important in surveying instruments where, owing to the varying distances, it is impossible to clearly 15 distinguish a target with an instrument of fixed power or to secure a field of sufficient width to locate such a target. By decreasing the magnifying power a wide field of 20 vision is provided in which the target may be easily located, and the power may then be increased to any desired extent to secure a narrower field with a clearer definition of any indicating characters which it may be desired to observe.

10 While reference has been made herein to the use of an erector and eyepiece system, still any desired arrangement of lenses may be used within the jointly and relatively adjustable lens-tubes to which the lens-holders 15 are applied. The instrument provides a simple, efficient, and economical construction of parts in which the adjusting-heads are disposed adjacent to each other and to 20 the eyepiece of the instrument, so that the magnifying power may be easily graduated and when adjusted to the proper extent readily focused upon the object to be viewed and the cross-lines of the instrument.

25 Having now described my invention and set forth its merits, what I claim, and desire to secure by Letters Patent, is—

30 1. In a telescope, a casing, cooperating lens-tubes, means for adjusting one of these tubes relative to the other, and a movable device carried by the casing and connected with said tubes for jointly adjusting them in their previously-adjusted relation.

35 2. In a telescope, a plurality of lens-tubes disposed one within another, a rotating head provided with means for adjusting one of said tubes relatively to the other, a telescope-casing, and a rotating head mounted therein and having means for jointly adjusting both

40 55 tubes within the casing.

3. In a telescope, a plurality of lens-tubes one of which is provided with a graduated face, and a rotating adjusting-head mounted in one of said tubes for adjusting the other

tube relative thereto and having cooperating graduations upon a face of said head.

4. The combination with a tube carrying an objective lens, of eyepiece and erector lenses mounted for independent and for joint movements, an adjusting device for regulating said independent movement, and a separate and independent adjusting device connected with the objective tube for regulating said joint movement.

5. In a telescope, a casing, a supporting-cap mounted therein and provided with a straight slot in the tube thereof, an adjusting-sleeve disposed within said cap and provided with a curved slot and an operating-head, a lens-tube disposed within said sleeve and provided with a block extending through the slots of the sleeve and cap, a collar secured in said lens-tube and provided with a straight slot therein, an adjusting-sleeve provided with a curved slot and disposed within said collar, and an eyepiece-tube provided with a block extending through the slots in said sleeve and collar.

6. In a telescope, a casing, a supporting-cap mounted therein and provided with a straight slot in the tube thereof, an adjusting-sleeve disposed within said cap and provided with a curved slot and an operating-head, a lens-tube disposed within said sleeve and provided with a block extending through the slots of the sleeve and cap, a collar secured to said lens-tube and provided with a straight slot therein, an adjusting-sleeve provided with a curved slot and disposed within said collar, a graduated eyepiece-tube provided with a block extending through the slots in head, sleeve and collar, and a graduated face upon the last-mentioned sleeve cooperating with the graduation of the eyepiece-tube.

7. In a telescope, a casing, a lens-tube adjustably supported therein, a collar threaded into said lens-tube and provided with a longitudinal slot, an adjusting-sleeve provided with a curved slot and disposed within said collar, a graduated eyepiece-tube disposed within said sleeve, a removable block upon the eyepiece-tube and extending through the slots of the sleeve and collar, and a graduated rotary adjusting-head for said lens-tube surrounding said tube.

In testimony whereof I affix my signature in presence of two witnesses.

GEORGE N. SAEGMULLER.
